(57) CLAIM

The ornamental design for a double shower tent assembly as shown and described.

DESCRIPTION

FIG. 1 is an overall view of a double shower tent assembly in a complete assembled state showing my new design;
FIG. 2 is another overall view of a double shower tent
assembly thereof viewing from the bottom;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is an enlarged view showing the portion 9 in FIG. 1;

FIG. 10 is an enlarged view showing the portion 10 in FIG.
1;

FIG. 11 is an enlarged view showing the portion 11 in FIG.
1; and,

FIG. 12 is an enlarged view showing the portion 12 in FIG.
2.

The broken lines depict portions of the double shower tent assembly that form no part of the claimed design.

1 Claim, 12 Drawing Sheets
